SEALING STRIP FOR ROLL TOP DOORS

Edward H. McCloud, Columbus, Ohio, assignor to
The Kinnear Manufacturing Company, Co-
lumbus, Ohio, a corporation of Ohio

Application January 11, 1932, Serial No. 585,968

7 Claims. (Cl. 20—20)

This invention relates to improvements in articulated roll top doors, and has for its object to provide, in connection with a door, means in the walls of a building adjacent the door to prevent 5 the formation of cracks and crevices between the door and the walls when the door is closed.

It is particularly the object of this invention to provide, in connection with a wall having on 10 the door jambs and the lintel, molding for engagement by the door when the door is closed, and cooperating with this molding and the door a strip for forming a substantially air-tight fit between the door and the molding.

While this improvement is particularly adapted 15 to be used with articulated doors, it may be used with other forms of vertically moving doors.

Referring to the drawings:

Figure 1 is a vertical longitudinal section 20 through a door and one wall of a building, showing the door in closed position. In this figure an old type of door and molding is shown.

In Figure 2 an inside elevation of the usual type of door is shown in closed position.

Figure 3 is a section on the line 3—3 of Figure 7. 25 Figure 4 is a section on the line 4—4 of Figure 3.

Figure 5 is a side elevation of one end of a door according to applicant's improvement. In this figure the door is shown in fragmentary parts.

In Figure 6 a slightly modified form of door 30 is shown from that shown in Figure 2.

Figure 7 shows another modification of the door used in combination with the other form shown in Figure 6.

Figure 8 is a section on the line 8—8 of Figure 35 5.

Figure 9 is a section on the line 9—9 of Figure 8.

Figure 10 is a section on the line 10—10 of Figure 6.

Figure 11 is a section on the line 11—11 of Figure 10.

Figure 12 is an inside view of the improved door showing in section the cooperating door and jamb structures.

Figure 12A is a section on the line 12A—12A of Figure 12.

Figure 12B is a section on the line 12B—12B of Figure 12.

Figure 12C is a section on the line 12C—12C of Figure 12.

Figure 12D is a section on the line 12D—12D of Figure 12.

Figure 12E is a section on the line 12E—12E of Figure 12.

In Figures 1 and 2 an old form of door is shown.

The object of this invention is to provide, in connection with the articulate door and wall structure shown in Figures 1 and 2, means to form a close fit between the door and the adjacent parts of the wall so that no air holes and vents are 5 allowed.

The wall around the door opening is indicated by the numeral 1, and has on each side of the door opening and across the top, molding 2. On each side of the door opening, attached to the wall and extending horizontally from the wall above the door, are trackways 3, one on each side, extending parallel to the wall and terminating in a section that is substantially horizontal above the door opening. The door for closing the 10 opening is composed of a plurality of sections 4, connected to one another by means of hinges 5. The door sections are supported and guided by means of rollers 6 in the trackways. These 15 rollers are located at each side of the door and serve to guide the door sections from a closed position to an open position and from an open to a closed position.

The trackways are supported on the adjacent 20 wall by means of brackets 7, which have foot members 8 attached to the wall by means of bolts or screws 9. The trackways are channel shaped, with one side of the channel bent to form a 25 groove in which the rollers operate, as clearly shown in Figure 3.

In order to cooperate with the moldings 2 there is provided on the inside of the wall, adjacent the molding, strips 10, one strip on each side of the doorway. The strips, as shown in Figure 3, extend partly over the moldings 2, forming with 30 the moldings benches. The door is cut away on each edge to form a notch 11, to receive one edge of one of the strips, and in order that there may be a wedging action between the strips on opposite sides of the doorway and the door the 35 upper ends of the strips 10 are narrower than the lower ends, so that the door may more readily enter as it descends to closing position between the two strips, and as the door descends it wedges between the two strips to form a close fit so there 40 is a substantially air-tight contact between the door and the adjacent strips and the adjacent moldings.

Figure 10 shows a section on the line 10—10 of Figure 6, while Figure 3 shows a section on 50 the line 3—3 of Figure 7, which shows a part of the door used in connection with the part shown in Figure 6. The door structure, as shown in Figures 6 and 7, involves a door and wedge-shaped strip engaging one edge of the door, and 55

5 a spring-pressed strip engaging the opposite edge of the door so that when the door is lowered between the two strips its opposite edges are engaged by the strips to form a tight sealing fit effected by the wedge-shaped strip and the spring-
10 operated strip. The upper end of the wedge-shaped strip being the thinnest, space is provided between the strips for the ready entrance of the lower end of the door as it is lowered to closing position.

10 By means of the joint structure between each edge of the door and the adjacent parts of the building any air passing in between the door and the jamb of the door passageway must make 15 at least two angles before it can enter the building. The air must pass between the door and a piece of the molding, and between the door and the strip 10, on the edge of the strip, and between the door and the strip 10, on the side of the strip. 20 By this means there is a substantially air-tight fit between the door and the adjacent wall structure. The strips 10 are held in position with relation to the wall of the building and the brackets 7 by means of a bracket 12, which is attached 25 to a strip 10 and to the bracket 7. There are several of these brackets 7 and several of the brackets 12.

30 The line of contact between the door and one of the strips 10 is indicated by the numeral 13, as shown in Figure 7. The broken line shown on the righthand side of Figure 7 indicates the line of contact between the door and the strip 10. This line indicates that the upper end of the line of contact between the door and the strip is to 35 the right of what it is in the lower end of the door, thereby producing a slight wedging action between the door and the strips as the door descends to closing position.

40 In the form shown in Figure 5 the door has no notch in one corner of each of its lateral edges. In this form the strip 10 abuts the edge of the door and cooperates with a molding to form a substantially air-tight closure between the door and adjacent wall structure. In the form shown 45 in Figures 5 and 8 the air in passing from the outside to the inside of the building, between the door and the jamb of the door opening, must make one right-angular turn, whereas in the structure shown in Figure 3 two such turns are necessary.

50 In Figure 8 the air passes in between the molding and the side of the door, and then between the end of the door and the strip 10. The structural features of the forms shown in Figures 3 and 8 are the same with the exception that in 55 Figure 3 the door has a notch therein to receive one edge of the strip 10, thereby forming a more complete seal.

60 In Figure 10 another form is shown. In this form the strip is indicated by the numeral 10a, and instead of being rigidly attached to the door jamb and to the brackets 12, is attached to have lateral movement with relation to the edge of the door. Each strip 10a is between the wall adjacent the door opening and the brackets 12, and 65 is supported therein by means of screws 16, which project into the strip and through slots 15 in the bracket 12. Each strip 10a is forced toward the door by means of a spring or springs 14, attached to each bracket 7 adjacent its foot 8. This spring is shown in Figure 11, acting to hold 70 the strip 10a in the extreme righthand position against the door.

75 Figure 12 shows a form of the door in which there is embodied applicant's improvements.

One edge of the door is notched and is engaged by a wedge-shaped strip so that as the door is closed it tends to wedge itself between oppositely disposed edge members. The other edge of the door is engaged by a resiliently supported strip so that as the door is lowered two instrumentalities operate upon the door to hold it in tight position so that it may have no lateral movement and no passageway is left for the entrance of air, and the like.

10 I desire to comprehend within my invention such modifications as may be embraced within my claims and the scope of my invention.

Having thus fully described my invention, what I claim as new and desire to secure by Letters 15 Patent, is:

1. In a door structure, in combination with a wall having a doorway therein and a trackway on each side of the doorway, an articulated closure movable along the trackways adapted to 20 engage the wall to close the doorway, said closure having a notch on one side at each edge, wedging means supported by the wall on one side of the doorway engaging the closure in the notch, and spring-pressed means on the other side of the 25 doorway and engaging the closure to form between the wall and the closure a tight fit.

2. In a door structure, in combination with a wall having a doorway therein and a trackway on each side of the doorway, a closure for said 30 doorway guided by the trackway, wedging means adjacent one trackway to engage said closure on one edge, and spring-pressed means to engage the other edge of the closure to form a tight fit between the closure and the wall when the doorway is closed.

3. In a door structure, in combination with a wall having a doorway therein and a trackway on each side of the doorway, a closure for said doorway guided by the trackway, said closure having a notch at one edge on one side, a wedge-shaped strip forming wedging means to engage said closure in said notch, and a spring-pressed strip engaging the other edge of the closure to 40 form a tight fit between the closure and the wall when the doorway is closed.

4. In a door structure, in combination with a wall having a doorway therein and a trackway on each side of the doorway, brackets for supporting the trackways, a vertically-sliding closure for said doorway having rollers engaging the 50 trackways, and sealing means supported by the brackets between the trackways and the wall to engage the vertical edges of the closure to form a tight closing fit.

5. In a door structure, in combination with a wall having a doorway therein and a trackway on each side of the doorway, brackets for supporting the trackways attached to the wall, an articulated closure vertically slidably along the trackways and adapted to engage the wall to 60 close the doorway, said closure having a notch on one side along each vertical edge, and sealing means supported by the brackets between the trackways and the wall to engage the vertical edges of said closure in said notches to form a 65 tight fit between the closure and the wall.

6. In a door structure, in combination with a wall having a doorway therein and a trackway on each side of the doorway, brackets for supporting the trackway, an articulated door for 70 said doorway guided by the trackway, said door having a notch on one side along each vertical edge, sealing strips forming wedging means supported on said brackets between the trackway and the wall to engage opposite edges of said 75

door in said notches, and yieldingly urged means tending to force the strips toward each other into the notches to form a tight fit between the closure and the wall when the doorway is closed.

5 7. In a door structure, in combination with a wall having a doorway therein and a trackway on each side of the doorway, brackets for supporting the trackways, a vertically-sliding closure for said doorway having rollers engaging the

trackways, and sealing means supported by the brackets between the trackways and the wall to engage the vertical edges of the closure to form a tight closing fit, said sealing means consisting of a yieldingly-urged movable strip on one side of the door and a rigidly mounted wedge on the other side, said rigid wedge being thinner at the top than at the bottom.

EDWARD H. McCLOUD.
